UNITED STATES PATENT OFFICE.

LOUIS J. ELSAS, OF ATLANTA, GEORGIA.

AUTOMATIC FEEDING APPARATUS FOR SEWING MACHINES.

Application filed January 27, 1923. Serial No. 615,244.

To all whom it may concern:

Be it known that I, LOUIS J. ELSAS, a citizen of the United States, residing at Atlanta, in the county of Fulton and State of Georgia, have invented certain new and useful Improvements in Automatic Feeding Apparatus for Sewing Machines, of which the following is a specification.

This invention relates generally to automatic feeding apparatus for sewing machines.

The principal object of the invention is to provide apparatus of the general type referred to which will automatically and without the intervention of an operator guide material or a succession of pieces of material through the stitching mechanism of a sewing machine to produce an arrangement of stitching in the material that exactly corresponds to and duplicates a predetermined design.

The invention includes the provision of means for feeding the material to the needle and in automatically changing the direction of travel of the material in accordance with the changing direction of the corresponding line of stitching in the original pattern or design. The means for feeding the material through the stitching mechanism preferably consists of a continuously traveling carrier belt against the surface of which the material is held by suction and moved through the stitching position. In connection with the material-carrying belt is employed means for releasing the suction and rotating the material to the right or the left to thereby produce a corresponding change in the direction of the line of stitching being produced. Preferably the manipulation of the material to produce the changes in direction of the stitched line are controlled electrically through the use of contact fingers which are arranged to make contact with a common terminal through perforations arranged in a moving belt in accordance with the pattern to be copied.

Other features of the invention will be hereinafter referred to.

In the drawings in which a preferred embodiment of the invention has been selected for illustration,

Figure 1 is a plan view partly in section and partly broken away of a sewing machine feeding device embodying the invention.

55

Figure 2 is a side view partly in vertical section of the device shown in Figure 1.

Figure 3 is a view similar to Figure 1 taken on a different level.

Figure 4 is a vertical section taken at 60 right angles to Figure 2.

Figure 5 is a view in detail and partly broken away of means for moving the material from side to side.

Figure 6 is a side view of the device shown 65 in Figure 5.

Figure 7 is a view in perspective of a pneumatic suction device forming part of the invention.

Figure 8 is a view in perspective of a raising and lowering device for the cloth manipulating device.

Figure 9 is a view in perspective of a supporting and guiding member for the cloth manipulating device.

75

Figure 10 is a diagrammatic view of an electric circuit system used in the control of the apparatus.

Referring to the drawings for a more detailed description of the invention, there is shown in Figure 1 an automatic feeding device embodying the invention and including a material carrying belt 5, a source of vacuum 18 for holding the material in engagement with the belt, a material manipulating and guiding device 7, and control mechanism including contact fingers 8 and a perforated belt section 9 for governing the operation of the material manipulating device 7.

90

The material carrying or feeding belt 5 passes about drums 10 and 11 suitably journaled in the framework 12^a of the machine. One of the drums as 10 is driven through a worm-drive connection between its shaft 12 95 and the shaft 13 of an electric motor 14 or any other suitable source of power. The belt 5 continuously travels in operation at a constant speed so that material deposited thereon is carried through the position of the sewing machine needle mechanism at 15 with the result that, unless the material is

100

directed from its normal course of travel a straight line of stitching will be produced therein parallel to the direction of travel of the material in its movement with the belt.

The referred to means for holding the material in engagement with the belt includes a vacuum chamber 16 which is connected through the pipe 17 with an exhausting pump 18 and driven from the motor shaft 13. Preferably a supplemental low-pressure chamber 19 is also provided which can be placed in communication with the main chamber 16 through the valve 20. Suitable suction nozzles 21 communicating with the supplemental exhaust chamber 19 engage the lower surface of the upper belt stretch and draw air therethrough by way of perforations 22 provided in the belt for that purpose.

It will be seen that the flow of air through the perforated belt holds the material in place against the belt surface.

The mechanism employed at 7 for manipulating and guiding the cloth or other material in its progress through the stitching mechanism includes a cloth engaging foot or member 25 whose under surface may be faced with soft rubber or other material for grasping or frictionally holding the engaged surface of the cloth when desired. The cloth engaging foot 25 forms the lower extremity of a hollow cylindrical member 26 provided with a peripheral flange 27 for engagement by a pair of lifting devices, a groove or runway 28 for engagement by a pair of friction driving wheels, and a circular frame member 29 holding a ring-shaped armature having two oppositely disposed pole pieces 30 arranged for cooperation with the pole pieces of a series of controlling magnet coils which operate to hold the cylindrical member and foot 25 in definite angular positions.

The lifting devices which engage the flange 27 consist of a pair of arms 31 provided with flange engaging rollers 32 and mounted on a rock shaft 33. The rock shaft 33 carries an operating arm 34' provided with a terminal armature member 35 mounted between the poles of a pair of oppositely disposed magnet coils 36 and 37 which function to depress or elevate the material manipulating member as desired.

The friction driving wheels 38 and 39, either of which may be brought into engagement with groove 28 of the rotatable cloth manipulating member 29, are mounted for rotation in opposite directions in a framework 34 which is pivotally mounted so that both friction wheels can be held normally out of engagement with the member 29 or either friction wheel swung into engagement with it to rotate the cloth manipulating member in either direction.

The friction wheels 38 and 39 are continuously driven through peripheral engagement with the intermediate wheels 41, one of which is fixed to the rotatable shaft 42 which carries a pulley 43 having a belt connection 44 by way of the guide pulleys 45 and 46 with the driving pulley 47 on the motor drive shaft 13 already referred to.

In order to swing either of the continuously and oppositely driven friction wheels 38 or 39 into engagement with the member 29 to correspondingly rotate the member, an arm 49 is provided on the friction wheel supporting framework 34 which terminates in an armature member 50 normally occupying a position midway between the pole pieces of a pair of oppositely disposed magnets 51 and 52. A suitable spring 53 holds the arm in its midposition and counteracts any tendency of the driven pulley 43 to rotate the framework out of its normal position.

In order to control the operation of the cloth manipulating device 7 electrical regulating devices are utilized which include the magnets 54 mounted in a circularly disposed arrangement in the annular frame member 55 in which the cloth manipulating member rotates. The magnets 54 are arranged in pairs in oppositely disposed relation, each pair of magnets being arranged to cooperate with the pole pieces 30 of the armature carried by the member 7 in order to hold the armature in the angular position represented by the pair of magnets.

Each pair of positioning magnets 54 is connected in circuit with an individual contact finger 8, the bank of contact fingers 8 being arranged to engage the surface of a section 9 of the belt 5 and to directly engage through suitable perforations 64 in the belt the surface of the roll or drum 10 which is made of electrically conductive material and connected through the conductor 57 with one of the brushes of a suitable electrical generator 58 driven by the motor drive shaft 13. The contact fingers 8 are individually connected through conductors 59 with different pairs of the positioning magnets 54 and to the other brush of the generator through the common return conductor 60, or through the raising and lowering magnets 36 and 37, the angular positioning magnets 51 and 52, or the valve 20 operating magnet 61. The valve 20 is brought to and held in its normal position by the weighted arm 62.

The order of operation of the several units of the apparatus may include the starting of the driving motor 14 to rotate the shaft 13 and thereby cause the operation of the belt drum 10, the exhaust pump 18, the electric generator 58, and the drive pulley 47 for the friction wheels 38 and 39.

The material to be sewed, which may be

any desired sheet material capable of being sewed, is placed on the carrier belt 5. Substantially coincidentally with the placing of the material on the belt one of the contact fingers 8 makes contact through a suitably elongated perforation in the belt and thereby energizes the valve magnet 61 to open the valve and cause suction to be applied to the perforated belt through the nozzles 21 to thereby hold the material in position on the belt. With this set of conditions established the material will be fed through the stitching position of the machine and a straight line of stitching will be produced in the material parallel to the path of travel of the belt 5 and the work carried thereby.

In order to change the direction of the line of stitching produced in the material, the perforation through which the contact finger in circuit with the valve magnet 61 comes to an end and the valve 20 is closed to shut off the suction which has been applied to the traveling carrier belt 5. Simultaneously with the cessation of the suction which held the material in place on the belt, the foot 25 of the material tender 7 is lowered into engagement with the material. Simultaneously one or other of the rotating high speed friction wheels 38 or 39 is swung into engagement with the runway 28 of the material tender 7 with the result that the cylindrical framework 26 of the tender 7 is rotated in either a clockwise or a counter-clockwise direction. When the cloth engaged by the foot 25 has been thus turned to effect the production of a line of stitching in the desired direction the corresponding perforation in the belt section comes to an end thereby releasing the engagement of the friction wheel with the runway 28. At the same time, in order to definitely stop the rotation at the desired angular position the proper pair of magnets 54 for the purpose are energized and serve to stop the rotation of the pole pieces 30 in alinement with the selected pair of magnets as will be clear. Simultaneously with this the lifting magnet 36 is energized to lift the foot 25 from the material while suction is again established by energization of the magnet 61 to again hold the material in fixed position on the belt while traversing the stitching position of the machine.

It will thus be seen that the position or arrangement of perforations in the belt section 9 will control changes in the direction of a line of stitching being produced in the material so that any predetermined design or outline will be mechanically and automatically copied without intervention or assistance by an operator other than to feed material to the device.

What I claim is:

1. In feeding apparatus for sewing machines, a conveyor belt for carrying material

through the stitching position, said belt containing perforations, suction nozzles cooperating with the perforations in the belt to hold the material in engagement therewith, means for relatively shifting the position of the material on the belt, and means for governing the suction to the nozzles during the relative shifting movement. 70

2. In feeding apparatus for sewing machines, a conveyor belt for carrying material 75 through the stitching mechanism of the machine, and means for changing the relative position of the material on the conveyor belt to change the direction of the line of stitching being produced. 80

3. In feeding apparatus for sewing machines, a conveyor belt for carrying material through the stitching position of the machine, a material engaging shoe normally held out of contact with the material, means for lowering the shoe into engagement with the material, means for rotating the shoe to the right or left to thereby change the angular position of the material on the belt, means for elevating the shoe out of contact 90 with the material, and electrical means for controlling the operation of the shoe, said electrical means including a perforated belt and contact fingers arranged to close controlling circuits through the perforations 95 in the belt. 100

4. In feeding apparatus for sewing machines, a conveyor belt for carrying material through the stitching position of the machine, suction means for holding the material against the belt, a material engaging shoe normally held out of engagement with the material, means for releasing the suction, and means for lowering the shoe into contact with the material, means for rotating the shoe to the right or left to change the angular position of the material on the belt, means for elevating the shoe out of contact with the material and restoring the suction holding means, and electrical means for controlling the suction and the operation of the shoe, said means including a perforated section of the carrier belt and contact fingers arranged to close controlling circuits through the perforations in the belt. 110

5. In a feeding apparatus for sewing machines, a conveyor for carrying the material through the stitching mechanism of the machine, means for holding the material in surface contact with the conveyor, means for relatively shifting the material on the conveyor, and means for releasing the hold on the material during the relative shifting of the material. 120

6. In a feeding apparatus for sewing machines, a conveyor for carrying the material through the stitching mechanism of the machine, suction means for holding the material in surface contact with the conveyor, means for relatively shifting the material

on the conveyor, and means to release the suction hold on the material during the relative shifting movement thereof.

7. In a feeding apparatus for sewing machines, a conveyor for carrying the material through the stitching mechanism of the machine, means for holding the material in surface contact with the conveyor, a rotatable member adapted to be thrown into sur-

face engagement with the material on the conveyor to change the angular position of the material with respect to the conveyor, and means for releasing the hold on the material when the rotatable member is in engagement therewith. 10 15

In testimony whereof I affix my signature.

LOUIS J. ELSAS.
